UNITED STATES PATENT OFFICE

ISRAEL GROLL, OF BROOKLYN, NEW YORK

DESIGN FOR A MONUMENT

Application filed March 3, 1930. Serial No. 34,726. Term of patent 7 years.

To all whom it may concern:

Be it known that I, ISRAEL GROLL, a citizen of Poland, residing at Brooklyn, in the county of Kings and State of New York, have invented a new, original, and ornamental Design for Monuments, of which the following is a specification, reference being had to the accompanying drawing, forming a part thereof.

The figure is a perspective view of the monument showing my new design.

I claim:

The ornamental design for a monument as shown.

In witness whereof I have signed my name to this specification.

ISRAEL GROLL.
